ELEVATED STORAGE TANK

Lloyd E. Anderson, Sr., Pittsburgh, Pa., assignor to Pittsburgh-Des Moines Steel Company, a corporation of Pennsylvania

Filed Sept. 11, 1962, Ser. No. 71,655

Term of patent 14 years

(Cl. D91—1)

Fig. 1

Fig. 3

FIG. 1 is an elevation of an elevated storage tank embodying my new design;

FIG. 2 is a plan view thereof; and

FIG. 3 is an enlarged fragmentary section along the line III-III of FIG. 1.

I claim:

The ornamental design for an elevated storage tank, as shown.
